UNITED STATES PATENT OFFICE.

FRANK L. GORMLEY, OF BROOKLINE, MASSACHUSETTS.

SPEED CONTROL FOR LIFTING JACKS.

Application filed April 4, 1925. Serial No. 20,643.

To all whom it may concern:

Be it known that I, FRANK L. GORMLEY, a citizen of the United States of America, and a resident of Brookline, county of Norfolk, State of Massachusetts, have invented certain new and useful Improvements in Speed Controls for Lifting Jacks, of which the following is a specification.

This invention relates to lifting jacks adapted to lower at high speed and has for its object the provision of means whereby the load may be retained in raised position under normal conditions by a rotatable worm, and its lowering readily controlled by the operator oscillating a lever and rotating said worm.

These objects are attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a vertical section of a lifting jack embodying the principles of the present invention, and

Figure 2 represents a section of the same on line 2, 2 on Fig. 1.

Similar characters indicate like parts throughout the several figures of the drawings.

In the drawings, 10 is a base having threaded thereto a housing 11, the upper end of which is provided with a bearing 12 for the ram or movable member 13.

The lower end of said ram 13 has secured therein a nut 14 to which is threaded the lifting screw 15 having keyed to its lower end a bevel gear 16 meshing with a bevel pinion 17 on an actuating shaft 18, on the outer end of which is mounted an actuating lever 19 of any well known construction.

The base 10 is provided with an upwardly extending annular flange 20 positioned on the top of the base 10, a plate 21 having an annular groove 22 in its upper face in

which are disposed a plurality of anti-friction members, such as the balls 23.

Superimposed upon these balls 23 is another plate 24 on the top of which rests the bevel gear 16.

By actuating the lever 19 the pinion 17 may be rotated and this rotary movement is transmitted to the lifting screw 15 through the gear 16, thereby causing the ram 15 to be raised within the housing 11.

Keyed to the actuating shaft 18 are two ratchets 25 spaced apart and between these ratchets is mounted a worm gear 26 which is adapted to be rotated only during the lowering of the load.

On the opposite sides of this gear 26 are two sets of spring pressed pawls 27, one set of which engage the teeth of one ratchet 25 at points intermediate the points of engagement of the other set of pawls 27 with its coacting ratchet 25.

In lifting the load the actuating shaft is rotated in the direction of the arrow *a* on Fig. 2, and when so actuated the rotating ratchets 25 will not engage the pawls 27 and no movement will be imparted to the worm gear 26.

This worm gear 26 meshes with the worm 28, the ends of which are mounted in bearings 29 in the housing 11, and the pitch of the thread of which preferably is such that it will not be rotated under the weight of the load.

To one end of the worm is secured a bevel pinion 30, the teeth of which mesh with a bevel gear 31 having a cylindrical stem 32 revoluble in a bearing 33 in a cover plate 34 secured in any well known manner to the housing 11.

The outer end of the stem 32 has a collar 35 secured thereto to prevent displacement of said gear 31.

The bearing for the actuating shaft 18 is also formed upon the cover plate 34 so that when said cover plate is removed all working elements are removed therewith except the lifting screw 15, its gear 16 and supports therefor, the worm 28, and the ram 13.

The cover plate 34 also has an extension 36 to which, at 37, is pivoted a lever 38 to which at 39 is pivoted one end of a link 40, the opposite end of which is pivoted to the gear 31 at 41.

The upper end of the lever 38 has formed thereon or secured thereto a cylindrical

member 42 in which is disposed the upper end of a tubular member 43, the lower end of which is provided with a V-shaped projection 44 adapted to engage the teeth 45 of the segment 46 formed upon or secured to the extension 36, thereby locking the lever 38 in adjusted position.

Within the tubular member 43 is threaded an annular nut 47 through which extends 10 a cylindrical handle 48 having a ball shaped knob 49 at its upper end and an annular flange or head 50 at its lower end.

Between the nut 47 and the upper end of cylindrical member 42 is a spring 51 which 15 is adapted to force the tubular member 43 downwardly into engagement with the segment 46.

When it is desired to operate the handle 48 the operator seizes the knob 49 and moves 20 it upwardly until the head 50 contacts with the nut 47 and then continues the upward movement until the spring 51 is compressed sufficiently to permit the disengagement of the projection 44 from the teeth 45.

25 The operator may then oscillate the lever 38 and through the link 40 impart rotary movement to the gear 31, through the pinion 30, worm 28, and worm gear 26.

As previously stated the thread of the 30 worm 28 has a pitch which will prevent its rotation by the rotation of the worm gear 26, and as a consequence the load upon the ram 13 will be sustained in its raised position until the worm 28 is positively rotated 35 by oscillating the handle 48.

The weight of the load upon the ram 13 has a tendency to move the ratchets 25 in the direction of the arrow *b* on Fig. 2, but 40 as the gear 26 is prevented from rotating by its engagement with the worm 28 and the pawls 27 are engaged with the worm 28, it is obvious that the ram will be prevented from moving downwardly.

When it is desired to lower the load the 45 operator oscillates the handle 48, rotating the worm 28 and worm gear 26, and as the pawls 27 on the latter move in the direction of the arrow *b*, the weight of the load on the ram 13 will cause the ratchet 25 to follow said pawls and remain in engagement therewith.

As long as the handle 48 is oscillated the load will continue to lower, but when said load has been lowered sufficiently the operator ceases to oscillate the handle and the projection 44 will immediately engage the teeth 45 and lock the handle so that no further lowering is permitted.

If the pitch of the thread of worm 28 is 60 such that under an excessive load the ram 13 commences to lower its downward movement may be readily controlled by means of the handle 48.

By this construction of lifting jack the 65 load on the ram 13 may be raised as desired.

and retained in its raised position until by manually operated mechanism the lowering of the ram under its load is permitted.

The jack does not lower automatically and is not lowered by means of a crank, but such lowering is wholly effected by the oscillation of the controlling lever.

The speed of lowering may be regulated by the operator actuating the controlling lever 38 faster or slower as the case may be. 75

Normally the jack is locked by the engagement of the projection 44 with the teeth 45 and the load cannot be lowered until this projection is disengaged from said teeth.

If desired the cover plate 34 may be dispensed with and a wall formed on the housing 11 to support the actuating shaft 18 and the elements coacting therewith.

It is obvious that whether or not the jack lowers automatically its lowering may be 85 wholly controlled by oscillating the controlling lever.

Other forms of gearing may be substituted for the bevel gears shown without affecting the principles of the present invention. 90

The worm gear could be secured directly to the shaft 18 and rotate during both the operation of lifting and lowering.

It is believed that the operation and many 95 advantages of the invention will be understood without further description.

Having thus described my invention, I claim:

1. In a lifting jack, the combination of 100 an actuating shaft adapted to be rotated in one direction to raise the load supporting member; two ratchets secured thereto; a gear interposed between said ratchets and loosely mounted on said shaft; pawls on the opposite sides of said gear adapted to engage said ratchets during the rotation of the shaft in the opposite direction, the pawls on one side engaging the teeth of one ratchet at points intermediate the engagement of the other set of pawls with the other ratchet; and means for controlling the rotation of said gear during the lowering of the load supporting member. 105

2. In a lifting jack, the combination of an actuating shaft adapted to be rotated in one direction to raise the load supporting member; two ratchets secured thereto; a worm gear interposed between said ratchets and loosely mounted on said shaft; pawls on the opposite sides of said gear adapted to engage said ratchets during the rotation of the shaft in the opposite direction, the pawls on one side engaging the teeth of one ratchet at points intermediate the engagement of the other set of pawls with the other ratchet; a worm meshing with the teeth of said gear; and means for controlling the rotation of said worm during the lowering of the load supporting member. 110 115 120 125 130

3. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; and mechanism for regulating the rotation of said worm including a manually controlled oscillating lever linked to a member rotatable with said worm.

4. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; a bevel pinion rotatable with said worm; a bevel gear in mesh therewith; a pin eccentrically disposed on said bevel gear; a pivoted lever; and a link between said pin and lever.

5. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; a bevel pinion rotatable with said worm; a bevel gear in mesh therewith; a pin eccentrically disposed on said bevel gear; a pivoted lever; means for locking said lever in fixed position; and a link between said pin and lever.

6. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; a bevel pinion rotatable with said worm; a bevel gear in mesh therewith; a pin eccentrically disposed on said bevel gear; a pivoted lever; automatic means for locking said lever in fixed position; and a link between said pin and lever.

7. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; a bevel pinion rotatable with said worm; a bevel gear in mesh therewith; a pin eccentrically disposed on said bevel gear; a pivoted lever; a fixed toothed

sector; a spring actuated member on said lever adapted to coact with said sector; and a link between said pin and lever.

8. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; a bevel pinion rotatable with said worm; a bevel gear in mesh therewith; a pin eccentrically disposed on said bevel gear; a pivoted lever; a fixed sector having depressions therein; a cylindrical member provided with a projection to engage the depression of said sector and having an annular flange on its inner wall and spaced from the bottom of said member; a casing on said lever in which said member is movable endwise; a handle extending through the top of said casing and having a shoulder on the lower end thereof adapted to engage said flange; a spring between said flange and the top of said casing.

9. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; a bevel pinion rotatable with said worm; a bevel gear in mesh therewith; a pin eccentrically disposed on said bevel gear; a pivoted lever; a fixed toothed sector; a cylindrical member provided with a projection to engage said sector and having an annular nut threaded to its inner wall and spaced from the bottom of said member; a casing on said lever in which said member is movable endwise; a handle extending through the top of said casing and having a shoulder on the lower end thereof adapted to engage said nut; and a spring between said nut and the top of said casing.

10. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; a member rotatable with said worm; and a manually controlled oscillating lever linked to said rotatable member and adapted to regulate the rotation of said worm.

11. In a lifting jack, the combination of an actuating shaft adapted to be rotated in one direction to raise the load supporting member; a ratchet secured thereto; a worm

gear loosely mounted on said shaft and carrying pawls adapted to engage said ratchet during the lowering of said load supporting member; a worm in mesh with said worm gear and the thread of which has a pitch sufficient to retain the load in raised position; a member rotatable with said worm and mechanism for regulating the rotation of said worm including a manually controlled oscillating lever linked to said rotatable member.

12. In a lifting jack, the combination of an actuating shaft adapted to be rotated in one direction to raise the load-supporting member; a ratchet secured thereto; a worm gear loosely mounted on said shaft and carrying pawls adapted to engage said ratchet during the lowering of said load supporting member; a worm in mesh with said worm gear; a bevel pinion rotatable with said worm; a bevel gear in mesh therewith; and manually controlled mechanism for rotating said bevel gear.

13. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; a bevel pinion rotatable with said worm; a bevel gear in mesh therewith; a pin eccentrically disposed on said bevel gear; a lever adapted to be oscillated and thereby rotate said bevel gear; means for locking said lever in fixed position; and a link between said pin and lever.

14. In a lifting jack, the combination of an actuating shaft adapted to be rotated in one direction to raise the load supporting

member; a ratchet secured thereto; a worm gear loosely mounted on said shaft and carrying pawls adapted to engage said ratchet during the lowering of said load supporting member; a worm in mesh with said worm gear and preventing its rotation under normal conditions; a bevel pinion rotatable with said worm; a bevel gear in mesh therewith; and oscillating means for rotating said bevel gear thereby rotating said worm and permitting the rotation of said worm gear under the weight of the load.

15. In a lifting jack, the combination of an actuating shaft adapted to be rotated in one direction to raise the load supporting member; a ratchet secured thereto; a worm gear loosely mounted on said shaft and carrying pawls adapted to engage said ratchet during the lowering of said load supporting member; a worm in mesh with said worm gear; a bevel pinion rotatable with said worm; a bevel gear in mesh therewith; and means for positively rotating said bevel gear and worm thereby permitting the rotation of said worm gear under the weight of the load.

16. In a lifting jack, the combination of a load supporting member; means for raising said member; and independent mechanism coacting with said actuating shaft for controlling the lowering of the load supporting member and including a manually actuated oscillating lever linked to a member rotatable with said worm.

Signed by me at 746 Old South Bldg., Boston, Mass., this 13th day of March, 1925.

FRANK L. GORMLEY.
